[57] CLAIM

The ornamental design for a portable welding machine,
as shown and described.

DESCRIPTION

FIG. 1 is an enlarged perspective view of a portable
welding machine showing my new design;

FIG. 2 is a front elevational view thereof;

FIG. 3 is a top plan view thereof;

FIG. 4 is a side elevational view taken from the right of

FIG. 2, the side opposite being a mirror image thereof;

FIG. 5 is a bottom plan view thereof; and

FIG. 6 is a rear elevational view thereof.

FIG. 2

FIG. 3

FIG. 4

FIG. 5

FIG. 6

FIG. 7
